(57) **CLAIM**

The ornamental design for a combined module and adapter for attachment to a hearing aid, as shown and described.

DESCRIPTION

FIG. 1 is a rear perspective view of a combined module and adapter for attachment to a hearing aid, showing my new design;

FIG. 2 is a bottom right perspective view thereof;

FIG. 3 is a left side elevation view thereof;

FIG. 4 is a rear elevation view thereof;

FIG. 5 is a right side elevation view thereof;

FIG. 6 is a left side elevation view of the module portion;

FIG. 7 is a rear elevation view thereof;

FIG. 8 is a right side elevation view thereof;

FIG. 9 is a top plan view thereof;

FIG. 10 is a right rear perspective view thereof;

FIG. 11 is a rear perspective view of the adapter portion;

FIG. 12 is a front perspective view thereof;

FIG. 13 is a bottom perspective view thereof;

FIG. 14 is a left side elevation view thereof;

FIG. 15 is a rear elevation view thereof;

FIG. 16 is a right side elevation view thereof; and,

FIG. 17 is a front elevation view thereof.
